DESIGN FOR A JERKIN APRON

Helene Pons, New York, N. Y.

Application November 15, 1943, Serial No. 111,692

Term of patent 3½ years

To all whom it may concern:

Be it known that I, Helene Pons, a citizen of the United States, residing at New York city, in the county and State of New York, have invented a new, original, and ornamental Design for a Jerkin Apron, of which the following is a specification, reference being had to the accompanying drawing, forming a part thereof.

Fig. 1 is a front view of a jerkin apron, showing my new design.

Fig. 2 is a side view thereof.

Fig. 3 is a rear view thereof.

Fig. 4 is a view of the jerkin apron shown in Fig. 1 with the front panel raised to show the overlap of the back panel.

I claim:

The ornamental design for a jerkin apron, substantially as shown.

HELENE PONS.
